UNITED STATES PATENT OFFICE.

JAMES HERVA JONES, OF ROCKFORD, ILLINOIS, ASSIGNOR TO EMERSON, TALCOTT & COMPANY, OF SAME PLACE.

DIVIDER FOR MOWING-MACHINES.

SPECIFICATION forming part of Letters Patent No. 380,900, dated April 10, 1888.

Application filed June 24, 1886. Serial No. 206,136. (No model.)

To all whom it may concern:

Be it known that I, JAMES HERVA JONES, a citizen of the United States, residing at Rockford, in the county of Winnebago and State of Illinois, have invented new and useful Improvements in Dividers for Mowing-Machines, of which the following is a specification.

My invention relates to a divider for use upon the outer end of a mowing-machine finger-bar, the object being to improve the general construction and details of this class of devices.

The invention consists in the combination, with a divider, of a winged guard extending inward of the divider.

The invention further consists in a supplemental divider of the construction to be fully described, and in the combinations of devices, hereinafter fully set forth.

In the accompanying drawings, Figure 1 is an outer side elevation of the divider and its appliances in place upon the outer end of the finger-bar. Fig. 2 is an isometrical representation of the adjustable runner of the divider. Fig. 3 is an isometrical representation of the winged cap of the divider. Fig. 4 is an isometrical representation of the supplemental divider. Fig. 5 is a sectional detail view illustrating the recessed portion of the divider and showing the manner of engaging the forward end of the runner. Fig. 6 is a plan view of the construction shown in Fig. 1; and Fig. 7 is a side elevation of the same, in part section, on the dotted line *zz*, Fig. 6.

A represents the divider fixed to the free end of the finger-bar of a mowing-machine. The divider is formed with a central vertical opening extending through its lower portion, and is provided with a semi-cylindrical bar, *a*, extending crosswise of the opening, connecting its opposite sides.

B represents the adjustable runner of the divider, having its forward end, *b*, produced in hook form to embrace transverse bar *a* of the divider, producing a self-locking connection. The rear upturned arm of the runner is

made vertically adjustable in its connection with the rear end of the divider by means of a clamping screw, *D*, in the usual manner.

The divider is provided with a winged guard, *E*, fixed to its upper surface and adapted to extend inward over the finger-bar and obliquely thereto, operating to carry the cut grass inward to prevent clogging the parts and deliver it to the track-clearer.

F is a supplemental divider having a detachable connection with the horn of the divider fixed to the free end of the finger-bar, and provided with a vertical rib, *f*, rising from its upper side forward of the holding-screw *g*, employed to fix it in position on the horn of the divider, and operates to carry the grasses over the holding-screw and prevent clogging.

Having fully described my invention, what I claim as new, and desire to secure by Letters Patent, is—

1. The combination, with the divider, of an independent wing-guard secured to the top of the divider near its front end and extending rearwardly therefrom along the upper and inner sides of the divider, the said wing-guard being of a hollow curved form in cross section and presenting an inwardly deflecting surface as it extends rearwardly along the divider, and being narrowed down at its forward end and provided with a depressed seat for the fastening-bolt, whereby the said guard may be secured to the divider without presenting an obstruction to the grass, substantially as set forth.

2. The combination, with the divider, of a supplemental divider having a detachable connection with the horn of the divider by means of a holding screw seated in the socket fitted over the horn of the divider and bearing upon the horn, said supplemental divider being provided with a guard-rib rising from its upper face forward of the holding-screw, substantially as set forth.

JAMES HERVA JONES.
